INTEGRATED PETROLEUM REFINING PROCESS
James W. Sprague, Streetsboro, Ohio, assignor to The
Standard Oil Company, Cleveland, Ohio, a corporation
of Ohio

Filed Dec. 4, 1962, Ser. No. 242,179
2 Claims. (Cl. 203—79)

The present invention relates to an integrated petroleum refining process involving a particular combination of a number of petroleum refining processes. The combination which forms the subject matter of this invention results in a process whereby crude oil is converted to substantially completely gasoline and lighter products with a minimum simultaneous production of products heavier than gasoline such as furnace oils and the like.

A substantial research effort is devoted by the petroleum refining industry to the development of ways and means for maximizing the amount of gasoline which may be obtained from a given quantity of crude oil. Efforts toward achieving this objective have been stimulated by the fact that, in general, gasoline is a more economically desirable product than heavier products such as furnace oil, diesel fuel, bunker fuel, and the like. The maximum amount of gasoline obtainable from a given quantity of crude oil has been limited by the available technology and further improvements in this area have awaited the development of new processing techniques. It is, therefore, one object of this invention to provide an integrated refining process by means of which it is possible to obtain a greater quantity of gasoline from a given quantity of crude oil than has been heretofore possible.

In brief, the invention relates to a process for the treatment of crude oil involving a combination of fractionation, catalytic reforming, fluorotreating, hydrocracking, and hydrogenation. The manner in which these processes are combined in accordance with the present invention can best be explained by reference to the attached patent drawing. In this drawing, the process is represented by a schematic flow diagram. Pumps, heat exchangers, valves and other conventional equipment are not shown on the drawing since they would add nothing to an understanding of the invention. A written description of the flow diagram now follows.

Referring now to the attached patent drawing, crude oil is introduced through line 10 into a crude still 11 where it is divided into four fractions, viz.;

- (1) An overhead fraction which includes the C₄ hydrocarbons.
- (2) A light naphtha fraction including C₅ and C₆ hydrocarbons.
- (3) A heavy naphtha fraction, suitable for reforming, having an end-point of 380° F.
- (4) A bottoms fraction having an initial boiling point of 380° F., and comprising the remainder of the crude oil.

The overhead fraction consisting of the lighter components is processed in a gas plant which is unrelated to the process of this invention and it leaves the process via line 12. The light naphtha fraction is recovered as a side stream of line 12a and can be transferred directly to fuel blending storage facilities and thereafter is not concerned with the integrated process of this invention. The heavy naphtha fraction is transferred through line 14 to a catalytic reforming unit 15. Effluent from the latter unit is transferred through conduit 20 to a fractionator 22 where a bottoms product boiling above about 380° F. is separated for further treatment which is described hereinafter. That fraction of the reformer effluent boiling below 380° F. is transferred from the frac-

2

tionator 22 via line 21 to the gasoline blending plant which is not a part of this invention.

The bottoms fraction obtained from the crude still 11 is transferred through line 13 to a fluorotreater unit 17. Hydrogen fluoride is added to the fluorotreater unit 17 through line 16. Treated product is transferred from the fluorotreater unit 17 through line 18 to a catalytic hydrocracking unit 19. Effluent from the hydrocracking unit 19 is transferred through line 23 to a fractionator 29. In the fractionator 29 the effluent from the hydrocracking unit 19 is divided into three fractions including a light ends fraction, a distillate fraction having an end point of 380° F. and a bottoms fraction having an initial boiling point of 380° F. The light ends fraction leaves the process via line 31 for further treatment in the gas plant which is not related to the present invention. The intermediate distillate fraction is transferred through line 30 to line 14 where it is mixed with the incoming feed to the catalytic reforming unit 15.

The bottoms fraction from fractionator 29 is transferred through line 27 to a catalytic hydrogenation unit 25 via line 23. Returning now to the bottoms fraction from fractionator 22, this fraction is also transferred by means of line 23 to the hydrogenation unit 25. Hydrogen is added to the hydrogenation unit 25 through line 24. Effluent from hydrogenation unit 25 is returned to the hydrocracking unit through lines 26 and 18. A detailed description of the various processing steps now follows.

In the first step in the process, crude oil is fractionated into four separate fractions. The first fraction comprises the lighter components of the crude oil up to and including the C₄ fraction. The second or light naphtha fraction comprises the C₅ and C₆ hydrocarbons. The third, or heavy naphtha fraction is suitable for reforming and has an end point of 380° F. The bottom fraction comprises those heavier components of the crude oil boiling initially at 380° F. A conventional fractionating tower comprising a plurality of bubble-cap trays may be used for a crude oil distillation of the type here contemplated.

The initial fraction of the crude oil comprising those hydrocarbons boiling up to and including the C₄ hydrocarbons is transferred to a gas plant for further treatment which forms no part of this invention. The second, or light naphtha fraction may be transferred to a fuel blending storage and is not further concerned with the integrated process of this invention. The third fraction of the crude oil, namely that portion having an end point of 380° F., is transferred to a conventional catalytic reforming unit.

Catalytic reforming units usually comprise a plurality of catalytic reactors, one or more of which may be periodically regenerated by burning coke from the catalyst. The catalyst employed in these reactors is a platinum-alumina catalyst comprising a small quantity of halogen and the composition and method of preparation of such catalysts are well understood in the art.

Catalytic reformers ordinarily include means for pretreating the feed. Virgin naphtha requires pretreatment, and when only this component of the feed is pretreated, the unit size is reduced, catalytic naphtha is sufficiently purified by the hydrocracking step. Such pretreater means are conventional and the pretreatment is usually accomplished by passing the feed over a bed of cobalt molybdate catalyst in the presence of added hydrogen so as to effect the removal of nitrogen and sulphur compounds from the feed as these compounds are known to have a deleterious effect on the platinum catalyst.

In general the catalytic reformer will be operated at pressures in the range of 500 to 900 p.s.i. and at temperatures in the range of 800 to 1000° F., the exact conditions depending upon the desired octane level of the product. Liquid hourly space velocities of one to six vol-

umes of hydrocarbon per volume of catalyst per hour are employed. A hydrogen-rich gas is separated from the reaction effluent and recycled to the reactors with the feed at a rate of 1000 to 10,000 s.c.f. of hydrogen per barrel of charge.

Effluent from the catalytic reforming unit is transferred to a conventional fractionator wherein a bottom fraction boiling above 380° F. is obtained and separated for further treatment in accordance with the process of this invention. The fraction boiling below 380° F. is transferred to a gasoline blending plant for further treatment which is not a part of this invention.

The bottom fraction of the crude oil, namely, that fraction boiling above 380° F. is transferred to a fluorotreater. In this treater the bottoms fraction is contacted with 0.5 to 1.0% of gaseous hydrogen fluoride based on the weight of the oil at a temperature in the range of 75 to 200° F. This treatment is designed to remove a part of the nickel and essentially all of the other metal contaminants normally contained in this fraction as well as any nitrogenous compounds which may be present since all of these materials are known to have a deleterious effect upon hydrocracking catalysts. Very small concentrations of these contaminants in the feed streams will lead to rapid poisoning of the catalyst in the subsequent hydrocracking process, whereas hydrogen fluoride will coagulate these contaminants and permit their ready removal without the formation of an acid sludge due to chemical reactions involving other constituents of the oil. The fluorotreating process is thus a selective one in which the yield of decontaminated oil is quite high, usually on the order of about 95%. Since the hydrogen fluoride is not consumed in the sludging reactions with the oil, it may be recovered and reused repeatedly. The material which is coagulated by the action of the hydrogen fluoride may be removed from the oil by any number of well-known separation methods, such as settling, filtration, or centrifugation. The effluent from the fluorotreating unit which is substantially free of deleterious metal and nitrogen compounds is next transferred to a hydrocracking process.

Hydrocracking processes are usually operated at pressures on the order of 500 to 5000 p.s.i., preferably in the range of 800 to 1000 p.s.i. and at temperatures in the range of 550 to 625° F. It is necessary to add hydrogen to the feed to a hydrocracker at a rate generally in the range of 1000 to 100,000 s.c.f. of hydrogen per barrel of feed, 5000 to 10,000 s.c.f. of hydrogen per barrel of feed ordinarily being sufficient. Space velocities on the order of 0.5 to 5 volumes of hydrocarbon per volume of catalyst per hour are employed.

Hydrocracking catalysts are of the so-called dual functional type. Such catalysts contain an acidic ingredient which serves as the cracking element in the catalyst and materials such as silica-alumina, silica-magnesia, silica-alumina-zirconia, beryllium oxide, indium oxide, fluorinated alumina or various acid-treated clays may be employed as the acidic constituent. The other element of the catalyst is the hydrogenation ingredient and it may be selected from the metals of Groups V to VIII of the Periodic Table and/or their oxides or sulphides. Illustrative of such materials are the oxides and/or sulphides of molybdenum, tungsten, vanadium, and chromium. Other materials such as the oxides of iron, nickel and cobalt may also be employed. In general the hydrogenating ingredient will comprise 0.1 to 20% by weight of the hydrocracking catalyst.

The effluent from the hydrocracking process is fractionated in conventional equipment into three fractions. The lightest fraction is transferred to a gas plant for further treatment which forms no part of the present invention. An intermediate fraction which includes the C₇ hydrocarbons and has an end point of 380° F. is combined with the pretreated virgin feed to the catalytic reformer. It has been observed that a hydrocracked dis-

tillate makes a better quality feed to the catalytic reforming process than a virgin material of the same boiling range and the process of this invention makes use of this fact.

The bottom fraction of the effluent from the hydrocracking unit which has an initial boiling point of 380° F. is combined with a bottom fraction having the same initial boiling point which is obtained by fractionation of the effluent from the catalytic reforming unit as described above. This combined stream is transferred to a catalytic hydrogenation unit and this step forms one of the key steps in the process. Neither of the materials making up this stream would make a satisfactory feed to a hydrocracking process because of the fact that they are largely condensed aromatic and consequently they are very difficult to crack. However, under severe hydrogenation conditions the relatively refractory aromatic compounds can be converted into naphthenic compounds which may be cracked with considerably greater facility. Hence, the hydrogenation step makes it possible to continue recycling the heaviest fractions from the hydrocracker and the reformer to virtual extinction so that only products boiling within the gasoline range or lighter are produced ultimately by this process.

Catalytic hydrogenation units are customarily operated at fairly high pressures on the order of 1,000 to 5,000 p.s.i. and preferably about 3,000 p.s.i. Temperatures on the order of 450 to 750° F. and preferably in the range of 500 to 600° F. are usually employed. Substantial quantities of hydrogen are required in the process and the ratio of hydrogen to hydrocarbon charge should be on the order of 2000 s.c.f. of hydrogen per barrel to 100,000 s.c.f. of hydrogen per barrel. The space velocity may vary from 0.5 to one volume of hydrocarbon per volume of catalyst per hour. A strong hydrogenation catalyst such as nickel or nickel supported on kieselguhr must be employed in this step of the process. The effluent from the hydrogenation unit is returned as feed to the hydrocracking unit where it is treated along with the virgin feed. Hence, the production of products heavier than gasoline is substantially eliminated.

A specific example of the process of this invention is as follows:

A desalted Illinois Basin crude oil having the properties listed in Table I was used.

The crude is introduced, at a rate of one thousand barrels per day, through line 10 into crude still 11 where it is divided into four fractions. The overhead stream, leaving the crude still by means of line 12, contains mixed butanes, produced at a rate of 21 barrels a day, and a dry gas portion produced at a rate 4560 standard cubic feet per day and having the composition indicated in Table II. Line 12 conveys this overhead stream to a gas plant for further processing not further concerned with the integrated process of this invention.

The catalytic reforming unit 15 is charged with 4425 pounds of a platinum-germanium on chlorided alumina catalyst (containing 0.35 percent platinum and 0.13 percent germanium) and is operated under conditions of a temperature of 925 degrees F., a pressure of 500 p.s.i.g., a weight hourly space velocity of 1.33 and 6000 standard cubic feet of recycle gas per barrel of liquid feed. The effluent from the catalytic reforming unit 15 is transferred through line 20 to a fractionator 22 where a fraction boiling below 380° F. is removed from the fractionator via line 21. This reformer product stream, when fractionated by equipment not otherwise directly concerned with the integrated process of this invention, produces 124,000 standard cubic feet of gas per day having the composition shown in Table V, 29 barrels per day of mixed butanes and 422 barrels per day of liquid reformate, having the properties shown in Table VI, which is transferred to the gasoline blending plant (not otherwise a part of this invention).

The bottoms fraction obtained from the crude still 11, having the properties shown in Table VII, is transferred at a rate of 695 barrels per day through line 13 to the fluorotreater unit 17. Hydrogen fluoride is added to the fluorotreater unit 17 through line 16 at a rate of 2050 pounds per day to produce 8,222 pounds per day of sludge containing 18 percent hydrogen fluoride. The supernatant fluorotreater stock is heated in a stream of inert gas at about 375° F. to remove dissolved hydrogen fluoride to produce 676 barrels per day of a treated stock having the properties shown in Table VIII. The sludge is heated to recover 98.6 percent of the total hydrogen fluoride which is then recycled to the fluorotreater.

It will be apparent from the foregoing description that the process of the present invention will offer important economic advantages to those petroleum refiners who desire to minimize their production of products heavier than gasoline. Many modifications of the process will undoubtedly occur to those skilled in the art and this application for Letters Patent is intended to cover all such modifications as would reasonably fall within the scope of the appended claims.

I claim:

1. An integrated petroleum refining process comprising the steps of
  - (a) fractionating a crude oil into an overhead fraction, a light naphtha fraction, a heavy naphtha fraction, and a bottoms fraction,
  - (b) subjecting said heavy naphtha fraction obtained in step (a) to a catalytic reforming operation,
  - (c) fractionating the catalytic reformate obtained in step (b) into at least two fractions,
  - (d) treating the bottoms fraction obtained in step (a) with hydrofluoric acid whereby nitrogenous and metallic compounds are removed therefrom,
  - (e) subjecting said treated bottoms fraction obtained in step (d) to a catalytic hydrocracking operation,
  - (f) fractionating the hydrocracked effluent from step (e) into a light fraction, an intermediate distillate fraction and a bottoms fraction,
  - (g) combining the intermediate fraction obtained in step (f) with the feed to step (b) and subjecting same to a catalytic reforming operation,
  - (h) combining the bottoms fraction obtained in step (c) with the bottoms fraction obtained in step (f) and subjecting this stream to a catalytic hydrogenation operation,
  - (i) combining the hydrogenated effluent from step (h) with the feed to step (e) and catalytically hydrocracking same.
2. An integrated petroleum refining process comprising the steps of
  - (a) fractionating a crude oil into an overhead fraction, a light naphtha fraction including C₅ and C₆ hydrocarbons, a heavy naphtha fraction having an

end-point of about 380° F. and a bottoms fraction having an initial boiling point of about 380° F.
 (b) subjecting said heavy naphtha fraction obtained in step (a) to a catalytic reforming operation,
 (c) fractionating the catalytic reformate obtained in step (b) into a light fraction, and into a heavy fraction having an initial boiling point of 380° F.
 (d) treating the bottoms fraction obtained in step (a) with gaseous hydrofluoric acid whereby nitrogenous and metallic compounds are removed therefrom,
 (e) subjecting said treated bottoms fraction obtained in step (d) to a catalytic hydrocracking operation,
 (f) fractionating the hydrocracked effluent from step (e) into a light fraction, an intermediate distillate fraction boiling within the gasoline boiling range and a bottoms fraction having an initial boiling point of about 380° F.

5
